ATTORNEY.

UNITED STATES PATENT OFFICE.

RICHARD A. LEAHY, OF BONNE TERRE, MISSOURI.

CONCENTRATOR CONSTRUCTION.

Application filed September 15, 1922. Serial No. 588,389.

To all whom it may concern:

Be it known that I, RICHARD A. LEAHY, a citizen of the United States, residing at Bonne Terre, in the county of St. Francois and State of Missouri, have invented certain new and useful Improvements in Concentrator Constructions, of which the following is a specification.

This invention relates to new and useful improvements in ore concentrators and its primary object is to provide in connection with a reciprocating table of the type commonly used for the concentration of ores, riffles of elastic material which by their inherent resilience effectually withstand the impact and abrasive action of material under treatment and thereby prolong the period of continuous efficiency of the apparatus and reduce the expense of maintaining the same in operative condition.

It is another object of my invention to provide a riffle of the hereinbefore described character which is re-enforced to resist deformation by contact with liquid used in the concentration of ores and which by its said re-enforcement is adapted for the retention of nails or other fastening means by which it is secured upon the surface of the table of which it is a part.

With the above objects in view my invention consists in providing a riffle made of vulcanized rubber re-enforced by a substance of less resilience. The elasticity of the rubber causes the riffle to withstand the impact and abrasion of the material passing across the surface of the concentrator, and its re-enforcement provides a stable support for the nails by which the riffle is secured to the reciprocating table. The re-enforcement furthermore gives to the riffle the vertical rigidity required to prevent its displacement or deformation by the movement of the material under treatment and it prevents swelling of the rubber by the moisture to which in wet concentration, it is continuously subjected.

An embodiment of my invention has been illustrated in the accompanying drawings in the several views of which corresponding parts are similarly designated and in which—

Figure 1 represents a plan view of a portion of a concentrating table equipped with my improved riffles;

Figure 2, a longitudinal section on the line 2—2, Figure 1;

Figure 3, an enlarged cross-sectional view of one of the riffles; and

Figures 4 and 5 similar views showing modifications in the form and arrangement of the re-enforcements of the riffles.

Referring further to the drawings, the reference character 5 designates the table of an ore-concentrator, usually composed of a base 6 and a covering 7 of linoleum, rubber or other suitable smooth-surfaced material.

The improved riffles which extend longitudinally of the surface of the table in order to retain, catch and direct values in comminuted material which, by a vibratory movement of the table, is subjected to an intermittently retarded advancing motion, are composed of an elongate body 8 of vulcanized rubber re-enforced by longitudinally embedded strips 9 of canvas or other suitable material.

The riffle is fastened to the table by nails 10 driven between adjoining plies of the re-enforcing fabric and it is preferred that the rubber covering the re-enforcement be thicker on the side receiving the direct impact of the material passing over the table, in order that the part 8^a of the riffle with which the material comes in contact shall have a greater degree of resilience, and consequently greater resistance to wear.

Another method of fastening the riffles consists in setting their lower portions in recesses or channels formed in the surface of the concentrator deck or table, as shown in Figure 4, in which case the nails may be made lighter or can be dispensed with.

In the form of my invention shown in Figures 2 and 3, the re-enforcing strips extend to the upper surface of the rubber body of the riffle, and in the modification illustrated in Figure 4, they terminate at a distance beneath said surface to provide a resilient top portion 8^c which increases the wear-resisting quality of the riffle and protects the fabric re-enforcements from the deteriorative effects of moisture.

The modified form of the invention illustrated in Figure 5 differs from the others in that the re-enforcement consists of rope 12 made of inter-twined fiber strands or twisted wires. The re-enforcement may also be made of rubber of less resilience than that of the body portion of the riffle, wood strips, wood fiber or other similar material.

Having thus described my improved con-

centrator construction, I desire it understood that modifications other than those shown and hereinabove described, may be availed of within the spirit of the invention; that the rubber body of the riffle may be of any form and proportions as are best suited to adapt it for use under different circumstances and conditions, and that the reinforcements may be made of any suitable material and in any desired form and thickness.

What I claim and desire to secure by Letters Patent is:

1. A concentrating table having laterally resilient riffles of reinforced soft rubber extending transversely to the flow of material across the surface thereof, and fastening members engaging with the reinforcements

to fix the riffles against bodily displacement on said surface.

2. As a new article of manufacture, a laterally resilient riffle for concentrating tables composed of an elongate body of soft rubber, and a longitudinal reenforcement embedded in said body at unequal distances from its sides.

3. As a new article of manufacture, a laterally resilient riffle for concentrating tables composed of an elongate body of soft rubber, and a longitudinal reenforcement embedded in said body between its sides and at a distance below its top.

In testimony whereof I have affixed my signature.

RICHARD A. LEAHY.
